UNITED STATES PATENT OFFICE.

LOUIS ARKIN AND SAMUEL ADELMAN, OF BOSTON, MASSACHUSETTS.

MOTION-PICTURE APPARATUS.

1,225,392.

Specification of Letters Patent.

Patented May 8, 1917.

Application filed January 8, 1917. Serial No. 141,131.

To all whom it may concern:

Be it known that we, LOUIS ARKIN and SAMUEL ADELMAN, citizens of the United States, and residents of Boston, in the 5 county of Suffolk and State of Massachusetts, have invented new and useful Improvements in Motion-Picture Apparatus, of which the following is a specification.

This invention relates to motion picture 10 apparatus, and its object is to provide apparatus of this general character which can be very economically manufactured adapting it for use as a toy, advertising device, or the like. A further object of the invention 15 is to provide apparatus of the kind specified which can be sold in knock-down and unassembled condition in a flat package suitable for mailing, and of such simple construction that it can readily be set up 20 and assembled by persons without mechanical skill and even by children.

Referring to the drawings which illustrate an embodiment of the invention,—

Figure 1 is a central longitudinal section 25 of the apparatus;

Fig. 2 is a horizontal section thereof;

Figs. 3 and 4 are perspective views of the box or casing showing opposite sides thereof;

Fig. 5 is a plan view of the blank of which 30 the casing is made;

Fig. 6 is a perspective view of the rotor with a picture secured thereto;

Fig. 7 is a plan view of the picture holding 35 member;

Fig. 8 is a similar view of one of the pictures;

Fig. 9 is a similar view of a drum head; and

Fig. 10 is a similar view of a fastener.

The box of casing A is made of any suitable inexpensive material, preferably cardboard, strawboard, or the like, and is formed from a blank of the shape and contour 45 shown in Fig. 5, adapted to be folded as indicated in said figure. The said blank is provided with a tab or picture retarder A' adapted to project into the box in the path of the pictures (Fig. 1) and with apertures 1, 2, 3, 4. When the blank is folded to form 50 the casing, the apertures 1 and 3 and 2 and 4 register and the box is opened at its top and front providing a sight aperture.

When the blank has been folded into the

form shown in Figs. 3 and 4 the prongs b 55 of the metal fastener B (Fig. 10) are bent downward and pushed through the box on opposite sides of the registering apertures 1 and 3, and then turned over to secure the fastener in position as best shown in Fig. 60 4. Another fastener B is similarly inserted on opposite sides of the registering apertures 2 and 4 and secured in position (Fig. 3) so that said box is thus secured by said two fasteners and is ready to receive the 65 drum or rotor.

The said drum or rotor consists of the picture holding member or strip C made of cardboard or other suitable material, having uniformly disposed picture holding slots c² 70 and mounted on the pair of metal drum heads D. Each of said drum heads is provided with projecting tabs or fasteners d, cut or split as shown, (Fig. 9), adapted to pass through the slots c in the strip C and 75 thereafter to be bent and turned over in opposite direction removably to secure the strip and heads as clearly shown in Fig. 6.

E are the pictures provided as best shown in Fig. 8 with an integral locking tab E' 80 having a relatively long toe portion e, pointed at its lower end, and a relatively shorter heel portion e' cut away at its bottom.

In securing the pictures to the holding 85 member or strip C, the locking tab E' is held at an angle to the strip, and the toe portion e of the tab inserted its entire length into a slot c². The picture is then swung upright so that the entire tab enters the 90 slot c² and is then slid in the direction of the heel portion e', i. e., toward the right as viewed in Fig. 6, until said heel portion passes beyond the edge of the slot c², whereupon the tab with its picture is securely 95 locked in position as clearly shown in said Fig. 6.

When the drum has been assembled and the series of pictures mounted thereon in the manner just described, it is placed with- 100 in the box or casing A with the slot apertures d' of the drum heads D in register with the slot apertures b of the fasteners B. A spindle F having a flattened portion f and a crank F' is then passed through the 105 apertures b' of the fasteners B and the slots d' of the drum heads, the flattened portion f of the spindle fitting within the slot d' of

one of the drum heads. The spindle is thus detachably secured to said drum and journaled in the fasteners B.

It will be clear that the apparatus having been thus assembled as shown in Fig. 1, rotation of the crank F' will rotate the drum with its series of pictures at the speed to produce the desired result, said pictures being viewed through the sight aperture 10 formed by the open front and top of the casing and the necessary retardation of the individual pictures being provided by the inwardly projecting tab or retarder A'.

A new series of pictures can readily be substituted either by removing and replacing the individual pictures or by the substitution of a new picture strip C, upon which the series of pictures has been mounted. The apparatus can be very economically manufactured and consequently sold at a price which permits its use as a toy, advertising medium or the like. Its parts are simple and can be readily assembled by anyone, and it can be safely mailed or otherwise transported in an envelop or other flat package, a great desideratum to its employment as an advertisement.

We claim:

1. In apparatus of the class described, 30 a knock-down casing having overlapping portions on opposite sides thereof, a pair of fasteners adapted to pass through said overlapping portions, a rotor mounted in said fasteners and a series of pictures radially disposed on said rotor.

2. In apparatus of the class described, a knock-down casing having overlapping portions on opposite sides thereof, a pair of fasteners adapted to pass through said overlapping portions, a rotor, a series of pictures radially disposed on said rotor, and a spindle engaging said rotor and journaled in said fasteners.

3. In apparatus of the class described, a 45 knock-down casing having overlapping portions on opposite sides thereof, a pair of fasteners adapted to pass through said overlapping portions, a rotor, a series of pictures radially disposed on said rotor, and a spindle detachably engaging said rotor and journaled in said fasteners.

4. In apparatus of the class described, a knock-down casing having overlapping portions on opposite sides thereof, a pair of fasteners adapted to pass through said overlapping portions, a rotor having a slot, a series of pictures radially disposed on said rotor, a spindle having a flattened portion adapted to fit within said slot, said spindle 60 journaled in said fasteners.

5. In apparatus of the class described, a casing, and a rotor comprising a pair of heads and a picture carrying member detachably secured thereto.

6. In apparatus of the class described, a

casing, and a rotor comprising a pair of heads having peripheral fasteners and a picture carrying member, said fasteners adapted to engage said member to secure said heads and member.

7. In apparatus of the class described, a 70 casing, and a rotor comprising a pair of heads having fasteners and a picture carrying member, said fasteners adapted to engage said member detachably to secure said 75 heads and member.

8. In apparatus of the class described, a casing, and a rotor comprising a pair of heads having split metal tabs and a picture carrying strip, said tabs adapted to pass 80 through said strip and thereafter to be bent to secure said heads and strip.

9. In apparatus of the class described, a casing, and a rotor comprising a pair of heads having split metal tabs and a picture 85 carrying strip having slots, said tabs adapted to pass through said slots and thereafter to be bent to secure said heads and strip.

10. In apparatus of the class described, a casing, a rotor having slots, a series of pictures radially disposed on said rotor, said 90 pictures having tabs locked in said slots, said tabs having toe portions and heel portions, the former relatively longer than the latter.

11. In apparatus of the class described, a 95 casing, a rotor having slots, a series of pictures radially disposed on said rotor, said pictures having tabs locked in said slots, and said tabs having pointed toe portions and cut away heel portions, the former relatively 100 longer than the latter.

12. In apparatus of the class described, a knock-down, one piece casing having a sight aperture and a picture retarder, fastening means for said casing, a rotor comprising a 105 pair of heads and a slotted picture carrying member, a series of pictures radially disposed on said rotor and having tabs locked in said slots and a spindle for said rotor mounted in said casing.

13. In apparatus of the class described, a knock-down, one piece casing having a sight aperture and a picture retarder, a pair of fasteners for said casing, a rotor mounted in said fasteners and comprising a pair of 115 heads and a slotted picture carrying member, and a series of pictures radially disposed on said rotor having tabs locked in said slots.

14. In apparatus of the class described, a knock-down, one piece casing having a sight aperture and a picture retarder, a pair of fasteners for said casing, a rotor comprising a pair of heads and a slotted picture carrying member removably secured thereto, a series of pictures radially disposed on said 120 rotor having tabs removably locked in said slots, and a spindle journaled in said fasteners and engaging said rotor.

15. In apparatus of the class described, a casing and a rotor comprising a pair of 125

heads spaced apart, and a picture carrying member secured to said heads and retaining them in spaced relation.

16. In apparatus of the class described, a 5 casing and a rotor comprising a pair of heads spaced apart, and a picture carrying member detachably secured to said heads and retaining them in spaced relation.

17. In apparatus of the class described, a 10 casing, a rotor comprising a pair of heads having peripheral fasteners, and a picture carrying member, said fasteners adapted to engage said member to secure said heads and member.

18. In apparatus of the class described, a 15 casing and a rotor comprising a pair of heads and a picture carrying strip, said heads having peripheral metal fasteners adapted to pass through said strip and there- 20 after to be bent to secure said heads and strip.

19. In apparatus of the class described, a casing, a rotor having slots, a series of pictures radially disposed on said rotor, said pictures having tabs extending through said 25 slots and adapted to engage the under side of said rotor to lock said tabs in said slots.

20. In apparatus of the class described, a 30 paper casing, a rotor comprising a pair of heads spaced apart and a picture carrying 35 member, each of said heads having an elongated slot, metal bearings in said casing having elongated slots registering with said slots in said heads, and a spindle journaled in said bearings having a flattened portion adapted to pass through said bearing slots and to fit within one of said drum slots.

Signed by us at Boston, Massachusetts,
this 4th day of January 1917.

LOUIS ARKIN.
SAMUEL ADELMAN.
